UNITED STATES PATENT OFFICE

EDWIN J. SCHWABE, OF FAR ROCKAWAY, LONG ISLAND, NEW YORK

VANITY CASE

Application filed November 13, 1928. Serial No. 319,065.

My invention relates to vanity cases, variously designated as vanity boxes, make-up boxes and the like, and commonly used by ladies and girls and also by theatrical performers, independently of sex, for holding various cosmetics, facial preparations, hair dressings, perfumes and similar articles.

My invention relates to fancy boxes of the general type here contemplated, whether used as vanity cases or otherwise.

More particularly stated, I seek to so construct the vanity case as to accomplish a number of distinct purposes, among which are the following:

15 First, to render the lid of the box entirely separate from the body portion thereof, thus avoiding the necessity for hinges or their equivalent.

Second, to render the lid reversible relatively to the body portion of the box, and removable therefrom, for use as a separate article, and particularly as a hand mirror.

Third, to enable the lid to be swung open and closed after the manner of a lid mounted 25 upon hinges, and to be rested in open position and at a suitable angle to the body portion of the box, after the manner of a hinged lid and used in that position as a mirror.

Fourth, to give the parts such construction 30 as to avoid the necessity for using hardware in the make-up of the device.

Reference is made to the accompanying drawing forming a part of this specification, and in which like reference characters indicate like parts throughout the several figures.

Figure 1 is a plan view of my improved vanity case, showing it as closed and the lid as with its ornamental face upward, the lid appearing as partly broken away.

40 Figure 2 is a plan view of the vanity case, the lid being reversed in position relatively to its location in Figure 1, so as to display to good advantage its mirror face.

Figure 3 is a section on the line 3—3 of Figure 1, looking in the direction indicated by the arrows.

Figure 4 is a section on the same line as Figure 3, but showing the lid as raised and as resting upon one of its edges, and thus 45 capable of use as a mounted mirror.

Figure 5 is a fragmentary section corresponding to the right side of Figure 4, the lid not being shown.

Figure 6 is a perspective of the lid, showing it used alone as a hand mirror.

A box member is shown at 7, and is provided with a bottom 8 and with one or more partitions 9. The box member 7 is further provided, adjacent its upper edge and parallel thereto, with a rabbet 11, extending nearly three-quarters of the way around its upper interior portion.

55 The rabbet 10 merges into a pair of notches 11, shown more particularly in Figures 1, 4 and 5.

The box member 7 is further provided with a rabbet 12, extending lengthwise of the box, from one of the notches 11 to the other, but at a level somewhat lower than that of the rabbet 10.

60 A lid for the box member is shown at 13, and carries a loop 14, made of ribbon, cloth, fancy leather or other light and flexible material, so as to serve as a handle for manipulation of the lid.

65 The lid 13 is further provided with an ornamental face 15, shown more particularly in Figure 1, and with a mirror face 16, shown in Figures 2 and 6.

The lid 13 is entirely separate from the 70 box member 7, and is so arranged that by aid of the loop 14 it may be swung upwardly and rested upon one of its edges, as indicated in Figure 4, or may be lowered into the position indicated for it in Figure 1. Again, it may be turned around so as to display to advantage its mirror face 16 instead of its ornamental face 15, as indicated in Figure 2.

75 With the lid 13 in the position indicated for it in Figure 1, if the operator grasps the loop 14 and raises the lid, the latter can be brought to rest upon its edge as indicated in Figure 4. The edge portion of the lid, immediately adjacent the notches 11, 11, moves

80 obliquely downward into these notches, so that most of the weight of the lid now rests upon the rabbet 12. When this occurs, the lid assumes a stable position, for the reason that the boundaries of the notches 11, 11 are engaged by the adjacent an-

gular portion of the lid 13, so that the lid is well supported and braced in its new position, as may be understood from Figure 4. As is obvious from this figure, if the lid 13 has any tendency to fall or to roll over to the right, according to this figure, any such tendency is defeated by the fact that any such rolling or turning movement must cause the sharp edge of the lid to press firmly against the rounded boundary of the notches 11, 11, thus supporting the lid in a position of stability.

With the parts in the position indicated for them in Figure 4 and as just described, the lid may be used as a mounted mirror, the mirror face 16 being suitably displayed for this purpose. If now the lid be lowered or swung downward so as to close the box as indicated in Figure 1, the ornamental face 15 will be displayed to advantage.

The lid may be picked up by hand and removed bodily from the box, and used as a hand mirror, as indicated in Figure 6.

Sometimes by way of variety, it may be desirable to rest the lid in position upon the box, with its mirror side 16 upward, as indicated in Figure 2. In this event the lid may be raised and lowered as before.

As may be noted from the construction of my device, no hardware need be used in putting together the various parts.

The frame of the lid 13 is preferably rendered ornamental, for instance by giving it the appearance of being grilled, as shown in Figure 1, though this is not essential to my invention.

I do not limit myself to the precise construction shown, as variations may be made therein without departing from my invention, the scope of which is commensurate with my claim.

Nor do I limit myself to any particular use for my box, as the same may be used in other ways than as a vanity case.

Having thus described my invention, what I claim as new and desire to secure by Letters Patent is as follows:

A vanity case comprising an open box and a lid separate from said box and detachably fitted thereupon, said lid being adapted to swing upwardly and to rest upon one of its edges, said box being provided with a rabbet extending lengthwise of the box and with another rabbet extending crosswise of the box, said rabbets being located at different levels, said box being also provided with a notch into which said rabbets merge, said notch and said rabbets being so located that said lid may rest flat upon one of said rabbets thus closing the box, or may rest with one of its edges in said notch and in engagement with the other of said rabbets.

Signed at Vienna, Austria, this 30th day of October, 1928.
